CLAIM

The ornamental design for a fingerprint lock box, as shown and described.

DESCRIPTION

FIG. 1 is a perspective view of a fingerprint lock box showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is another perspective view thereof, shown in a closed position; and,

FIG. 10 is an enlarged portion view labeled, "FIG. 10," in FIG. 2.

The even dashed broken lines in the drawings depict portions of the fingerprint lock box that form no part of the claimed design. The dashed-dot lines show the boundary of

(Continued)

the enlarged portion view of FIG. 10 in FIGS. 2 and 10 and form no part of the claimed design.

1 Claim, 10 Drawing Sheets
